UNITED STATES PATENT OFFICE.

GUSTAV MAIER, OF SCHRAMBERG, GERMANY.

BOX-COVER FASTENING.

1,103,976.

Specification of Letters Patent.

Patented July 21, 1914.

Application filed August 26, 1913. Serial No. 786,688.

To all whom it may concern:

Be it known that I, GUSTAV MAIER, a subject of the Emperor of Germany, residing at Schramberg, Germany, have invented new and useful Improvements in Box-Cover Fastenings, of which the following is a specification.

This invention relates to fastening devices for securing covers on boxes, more particularly on boxes of paper board or like material having covers which telescopically fit over said boxes, and has for its object to provide a simple, inexpensive fastening means or lock made in whole or in part of the material of the box and its cover, and when so made, formed simultaneously with the blank of said box and cover. This fastening which can be made with little or no additional expense forms a secure lock for holding covers on boxes that are used for mailing purposes, delivering merchandise and other articles, and for various other purposes unnecessary to mention, there being practically no danger of the cover becoming loosened or lost by accident or other cause, and furthermore by means of this lock the cover is held so securely that no extraneous fastenings, such as string, paper, or seals, are required, thus permitting a great saving in time as such fastenings are often not at hand when desired.

In the accompanying drawing, Figure 1 is perspective view of a covered box with the invention applied thereto. Fig. 2 is a vertical sectional view through one side of the box on the line 2-2 of Fig. 1. Fig. 3 is a fragmentary view of a portion of the box cover showing that part of the fastening device formed therewith. Fig. 4 is a fragmentary view of a portion of the box and the locking loop thereon. Fig. 5 is a horizontal sectional view on the line 5-5 Fig. 4. Figs. 6 and 7 are detail views showing modified forms of the invention.

In the drawings, 10 indicates a box which may be made of cardboard, paper-board, or other like material and 11 a cover therefor, which fits telescopically over the box, and may extend to the bottom thereof as shown, or to some point between the top or bottom as desired. Fastened to the box on one, two, or more sides, is a keeper preferably in the form of a flat loop 12 made in the present instance of thin sheet metal, said loop or loops projecting from the side or sides preferably a distance equal to the thickness

of the material forming the box cover. The loops 12 are each made in the form of a staple with two straight parallel legs 13 connected by a straight strip 14 that forms the outer portion of the staple, the legs 13 being forced through the side of a box and bent toward each other as at 15, Fig. 5, thereby holding the staple in position to receive the coöperating member on the cover. In one aspect the tongue 16 and the bifurcated slot which forms it may be considered as consisting of an opening from the upper edge of which the tongue extends so as to project into or over the opening.

At suitable points in the sides of the cover 11 are formed tongues 16 made by cutting U-shaped slots 17 in said sides which may be done at the time the blanks for forming the cover are made. These tongues each engage a loop 12 by slipping thereinto as the cover is being placed upon the box, the loop 12 itself lying within the slot 17, the horizontal portion 17a thereof passing under the lower edge of the loop, thereby forming a lock by means of which the cover is retained in place on the box. To remove the cover the lower portion 18 thereof below the tongue is sprung outwardly as indicated in dotted lines, Fig. 2, until released from said loop whereupon the cover may be easily withdrawn from the box. It is to be understood, of course, that each fastening device is to be disconnected in the same way before the cover is withdrawn. To render the act of disconnecting the fastening or lock more easy, that is, to give flexibility to the fastening I prefer to provide slots or notches 19 cut upwardly from the lower edge of the cover on each side of the U-shaped slot 17. This forms a lip as it were of the part 18, which may be easily bent outward when the fastening is to be disconnected. In Fig. 3 the bottom of the lip 18 has been cut away to enable the finger to more readily engage therewith. This, however, is not necessary as the lip may be made as shown in Fig. 6, where it extends down to and in line with the bottom of the cover 11. The tongue 16 projects downwardly as shown in Fig. 3 and has straight sides, and a straight lower edge at right angles to said sides. This straight edge may, however, be semi-circular in form, as in dotted lines Fig. 6. Instead of making the loop 12 of sheet metal it may be made integral with the box, as in Figs. 6 and 7. As there shown two horizontal slots, 20, 21,

one above the other in parallel relation, are cut through the side of the box on which the loop is to be formed and the strip between said slots bent outwardly, sufficiently far to permit the tongue 16 on the cover passing thereto when the cover is placed upon the box. The outer side of the loop 22, as in the case with the loop 12, is substantially flush with the outer surface of the box cover.

10 What I claim is:—

1. A fastening device for locking covers on boxes comprising a keeper on the side of the box and coöperative securing means on the 15 cover comprising an extension lying wholly in the plane of the wall of said cover, to engage the interior of said keeper, and an opening in which said extension lies having an edge adapted to engage the underside 20 of said keeper.

2. A fastening device for locking covers on boxes comprising a keeper on the side of the box and coöperative securing means on the cover comprising an extension lying 25 wholly in the plane of the wall of said cover, to engage the interior of said keeper, and an opening in which said extension lies having an edge adapted to engage the underside 30 of said keeper, said extension consisting of a tongue integral with the said cover.

3. A fastening device for locking covers on boxes comprising a keeper on the side of the box and coöperative securing means on the cover comprising an opening, and a 35 tongue lying wholly in the plane of the wall of said cover, projecting into said opening from the upper edge of said opening, said opening receiving said keeper and having an edge engaging the underside of said keeper, said tongue passing into said keeper.

40 4. In combination a box having a body with a loop on the side thereof, a cover having a substantially U-shaped slot formed therein, thereby forming an integral tongue

on said cover, said U-shaped slot receiving 45 the sides of said loop and said tongue extending through said loop, so that said loop extends across the axis of said tongue.

5. In a fastening device for box covers, a box having an outwardly projecting loop on 50 each of two sides, combined with a cover having downwardly projecting integral tongues on similar sides, said cover having adjacent each tongue a bifurcated slot, each of said tongues adapted to engage a loop 55 while the cover is being placed on the box, and said loops to enter the said slots after the cover is in place, thus locking the cover on the box, said fastening devices lying substantially flush with the outer surfaces of the 60 cover.

6. In a fastening device for box covers, a box provided with an outwardly projecting flat loop on two or more sides, combined 65 with a cover having an integral lip on corresponding sides, with substantially parallel notches extending upwardly from the edge of said side at the sides of said lip, and integral tongues formed by a bifurcated slot in each lip, each of said tongues adapted to 70 enter a loop and each lip to extend around the loop, said loop and lip lying substantially flush with the outer surface of the cover.

7. A box having an outstanding loop projecting from a side wall thereof, and a cover 75 having a U-shaped slot in a side wall thereof forming a tongue and an adjacent shoulder, the said tongue being adapted to enter the said loop and the shoulder adapted to underlie the lower edge of the loop to prevent 80 withdrawal of the cover from the box.

In testimony whereof I have hereunto set my hand in presence of two subscribing witnesses.

GUSTAV MAIER.
